UNITED STATES PATENT OFFICE.

THOMAS LESLIE BODIE, OF WINNIPEG, MANITOBA, CANADA.

COMBINED GRAIN RECLEANER AND GRADER.

Application filed April 24, 1926, Serial No. 104,345, and in Canada March 9, 1925.

The invention relates to improvements in combined grain recleaners and graders and an object of the invention is to provide a machine which will effectively clean the various 5 grains and which can be utilized to grade the cleaned grain.

A more particular object of the invention is to provide a specially constructed discharge spout for receiving the initially cleaned grain 10 from a reciprocated shoe or such like, the discharge spout being associated with a blower fan and being adjustable in position and also adjustable in size and being provided with an adjustable gate to vary the size of the discharge opening.

A further object of the invention is to provide a fan construction which will effectively distribute the blast within the spout.

With the above more important objects in 20 view, the invention consists essentially in the arrangement and construction of parts hereinafter more particularly described, reference being had to the accompanying drawings, in which:—

25 Fig. 1 is a side view of the machine.
Fig. 2 is a plan view thereof.

Fig. 3 is an end view of the machine.

Fig. 4 is a vertical sectional view centrally through the machine at 4—4' Figure 2.

30 Fig. 5 is an enlarged detailed horizontal sectional view at 5—5' Figure 4.

Fig. 6 is a cross sectional view at 6—6' Figure 4.

Fig. 7 is a perspective view of the riddle 35 or scraper.

Fig. 8 is a perspective view of the fan.

Fig. 9 is a side view of the eccentric cam and straps, the driving shaft being shown in vertical section.

40 Fig. 10 is a perspective view showing one of the side bars which support the fan casing.

In the drawings like characters of reference indicate corresponding parts in the several figures.

45 The frame of the machine is of the customary type presenting the usual corner legs 1 connected by upper, lower and intermediate side bars 2, 3 and 4 and by front and rear cross bars 5 and 6. Brace bars 7 and 8 are 50 also provided to reinforce the sides of the machine.

The upper part of the frame supports a hopper 9 which is provided with an adjustable gate 10 controlling the discharge through 55 the feed outlet 11. Underlying the hopper 1

locate an inclined reciprocated shoe 12 which is constructed as now described. It presents a trough-shaped body embodying a bottom 13 and opposing side walls 14. Within the body I mount an upper screen 15 and an under screen 16 and beneath the screen 16 and sliding on the bottom I locate scraper 17 which is adapted to keep the under side of the screen 16 clean. The riddle is formed from a number of suitably spaced cross bars 18 (see Figure 7) connected by lengthwise extending parallel tie bars 19.

The forward end of the screen 15 discharges onto a plate 20 and the plate directs the grain to a laterally discharging chute 21. The screen 16 discharges grain onto a cross plate 22 which extends beyond the rear end of the shoe and has the rearmost end thereof curved downwardly. A laterally discharging chute 23 is arranged to receive the grain discharging over the rear end of the bottom plate 13. The shoe is supported for vibratory movement by front and rear pairs of hangers 24 having their lower ends pivotally attached to the sides 14 and their upper ends pivotally 80 swung from the upper side bars of the main frame.

The main driving shaft 25 of the machine is rotatably mounted in suitable bearings carried by the intermediate bars 4 and in a location adjacent the forward end of the shoe. A fan shaft 26 is rotatably mounted in suitable bearings 26' carried by the lower bars 3 and is located underneath the rear end of the shoe. A fan 27 is secured to the shaft 26 and is formed in the manner best shown in Figure 8 where it will be observed that the blades 28 thereof are carried by radiating end arms 29 extending from hubs 30 and that between the blades which are positioned 90 degrees apart, I locate segmental divisional plates 31 having their ends riveted centrally to the blades. The object of these plates 31 will be later described.

The fan operates within a substantially 100 cylindrical fan casing 32, the fan casing having openings 33 in the ends thereof to permit exterior air to enter the casing. The casing is rotatably mounted on the shaft 26 and to this end I secure horizontally disposed bars 105 34 to the ends of the casing, these bars being fitted with upstanding bearings 35 rotatably receiving the shaft 26 (see Figure 10). Gates 36 are pivotally attached to the ends of the casing and by opening and closing these, I 110

can control the amount of air admitted through the openings 33. The gates are supported by swinging bars 37 which operate over toothed racks 38 secured to the casing 5 sides, the teeth of the racks holding the bars 37 in any adjusted position.

- A discharge spout indicated generally by the reference numeral 39 is attached permanently to the fan casing, the upper end of 10 the spout being substantially vertical whilst the lower end thereof curves inwardly and downwardly and meets the lower part of the casing tangentially. The spout is formed from two main parts, a non-adjustable body 15 portion 40 and an adjustable rear portion 41, the body portion comprising an inner plate 42 having the lower end curving inwardly and secured to the fan casing and the upper end curving rearwardly and forming a hood 43. 20 To the latter plate I secure opposing wooden side boards 44 and to the inner faces of these side boards I fasten metallic plates 45 which have their lower ends curving inwardly and downwardly and communicating with the 25 sides of the fan casing. Between these side plates the adjustable rear portion 41 of the spout is located, such rear portion being of a trough-shape and presenting opposing vertically extending side wings 46. The side 30 wings are fitted with parallel inclined slots 47 which receive pins 48 carried by the side plates 45 with the result that the portion 41 of the spout can be moved towards and away from the front portion 40 to increase 35 or diminish the cross sectional area of the spout as desired.

To the lower ends of the wings 46 I secure spaced pairs of batons 49 and 50 and these 40 slidably receive a downwardly and inwardly inclining deflector plate or chute 51 formed continuous with the body plate 41 and inclining in the same direction as the slots 47. An extension plate 52 passes tangentially from the lower side of the fan casing and 45 has the ends thereof connected to the side plates 45 and the rear end of the plate 52 overlies the plate 51 to provide a discharge passage 53 for grain. To the upper end of the plate 41 I secure a cross board 54 and this 50 cross board carries a hinged gate 55 at its upper edge. An upstanding divisional board 56 is secured centrally to the extension plate 52 to divide the blast emanating from the fan.

From the above it will be apparent that 55 when the fan is rotated in the direction indicated by the applied arrow Figure 3, there will be a blast outwardly and upwardly through the spout and that I can vary the velocity of the blast within the vertical portion of the spout by increasing or diminishing the cross sectional area of the spout through the adjustment of the rear portion 41 thereof.

Means is provided for adjusting the rear portion of the spout, such embodying an 60 upper pair of levers 57 attached pivotally at

58 to the portion 40 of the spout and pivotally connected at 59 to the portion 41 thereof and a pair of bell cranks 60 similarly connected to the spout parts, one of the arms of each bell crank being arranged to ride over a 70 toothed quadrant 61 attached to the non-adjustable side of the spout. Obviously by swinging the bell cranks up or down, I widen or diminish the width of the spout.

The inner side of the spout carries a feed 75 trough 62, the upper end of which underlies the plate 22, the arrangement being such that grain discharging from the plate onto the trough 62 will be delivered to the interior of the spout and will fall within the spout 80 in a stream extending completely across the spout so that the upgoing blast from the fan passes therethrough.

A stationary hopper 63 is located beneath the fan casing and is adapted to receive the 85 grain discharging from the lower end of the chute 51. A conveyor trough 64 communicates with the hopper and extends forwardly and upwardly being suitably supported by a cross bar 65 extending between the front legs. 90 The trough supports rotatably, upper and lower conveyor shafts 66 and 67 provided with rollers 68 and the rollers carry an endless belt which is fitted with suitably spaced slats 69 adapted in the rotation of the belt to 95 gather the grain in the hopper 63 and sweep it upwardly over the bottom of the trough and discharge it at the front end of the machine.

The shaft 25 is fitted with similar eccentrics 70 receiving straps 71 located at the 100 front ends of pitmans 72, the rear ends of which are connected pivotally at 73 to the sides of the shoe 12. The brace bars 8 support a cross rod 74 which carries a pair of hooks 75, the hooks being caught in holes 105 76 located in the forward ends of the bars 19.

The shaft 25 is supplied at the opposite ends with pulleys 77 and 78 and centrally of its length with a chain wheel 79. The pulley 77 is used as the driving pulley and that 110 78 is connected by a cross belt 80 to a pulley 81 secured to the fan shaft. The chain wheel 79 is connected by a chain 82 to a chain wheel 83 secured to the shaft 66.

According to the above arrangement when 115 the pulley 77 is rotated in the direction indicated by the applied arrow Figure 1, the fan and conveyor are driven in the directions indicated by the applied arrows in Figure 4 and the shoe is reciprocated.

Owing to the riddle or scraper being held stationary whilst the shoe is reciprocated, the riddle serves effectively to clean the under side of the screen 16.

The upper end of the spout is adjustably 125 supported from the main frame by utilizing adjusting bolts 84 attached to the side boards 44 of the spout and operating in slots 85 formed in bars 86 attached to the frame, the slots being more or less radial to the shaft 26. 130

When this machine is to be used for cleaning the heavier grains such as wheat, rye and peas, the spout is brought to its most vertical position and the rear portion 41 thereof is closed in to give the smallest cross sectional area to the spout. This increases the force of the up going air blast within the spout and also gives a somewhat shorter travel for the grain falling down in the lower part of the spout from the trough 62. The dust, chaff and lighter seeds are blown out the upper end of the spout in the blast and the heavier grain is discharged through the opening 53 to the hopper 63 from which it is elevated by the conveyor.

When one is recleaning somewhat lighter grains such as barley and oats, the spout is adjusted by means of the bolts 84 to give it a somewhat inclined position and the rear portion 41 thereof is also moved back to increase the cross sectional area of the spout. This decreases the velocity of the blast and gives a somewhat longer travel to the grain falling across the spout from the trough.

When light grains such as brome and rye grass seed are being recleaned, the spout is given a considerable inclination and the adjustable part of it is well opened up to give a large cross sectional area. Such results in a decrease in the blast and a longer travel of the falling grain.

Whilst I have entered into a detailed description of the manner in which the spout is formed so that it can be adjusted to vary the cross sectional area and have also given a detailed description of the manner in which it is held in its various inclined positions, it will be readily understood that such structures could be easily modified without departing from the spirit of the invention.

I might point out also that the shoe operates to initially clean the grain and that the spout and fan blast are utilized to reclean the grain discharging from the shoe. Obviously the arrangement of the shoe for initially cleaning the grain could be modified as the novel features of the invention reside more particularly in the spout and fan rather than in the particular type of shoe used for ini-

tially cleaning the grain prior to its delivery to the spout.

I have found that by providing the divisional plates 31 and the board 56 I effectively distribute the air blast in the spout.

What I claim as my invention is:

1. In a grain recleaning device, a pivotally mounted fan casing, a driven rotatably mounted air blast fan within the casing, an upwardly extending spout having the lower end continuous with the casing and the upper end thereof adjustably supported thereby permitting of the spout taking various inclined positions, means for feeding the grain to be cleaned into the spout to fall in a distributed stream across the up going air blast within the spout, means for discharging the cleaned grain from the lower end of the spout and means whereby the spout can be adjusted to increase or diminish the cross sectional area thereof and to increase or diminish the travel of the falling stream of grain there across.

2. In a grain recleaning device, a rotatably mounted fan casing, a driven air blast fan rotatable within the casing, an upwardly extending inclining spout having the lower end thereof carried by and communicating with the interior of the fan casing, said spout having front and rear walls, sectional side walls connecting the front and rear walls and adjustable to vary the distance between said front and rear walls to thereby vary the cross sectional area of the spout, a feed trough opening through the front wall of the spout and adapted to feed the grain to be cleaned in a falling stream across the lower end of the spout, the arrangement being such that adjustment of the spout to vary the cross sectional area thereof results in a lengthening or shortening of the path of the falling stream of grain through the spout and a discharge chute located at the lower end of the spout and at the under side and beneath the falling stream of grain.

Signed at Winnipeg, this 19th day of April, 1926.

THOMAS LESLIE BODIE.
